UNITED STATES PATENT OFFICE

171,100

FLEXIBLE SHEET OF CUSHIONING
MATERIAL OR THE LIKE

Lester Pannone, Shelton, Conn., assignor to The Sponge Rubber Products Company, Shelton,
Conn., a corporation of Connecticut

Application June 20, 1952, Serial No. 20,287

Term of patent 14 years

(Cl. D87—3)

To all whom it may concern:

Be it known that I, Lester Pannone, a citizen of the United States, residing at Shelton, in the county of Fairfield and State of Connecticut, have invented a new, original, and ornamental Design for a Flexible Sheet of Cushioning Material or the like, of which the following is a specification, reference being had to the accompanying drawing, forming part hereof.

Fig. 1 is a plan view of a flexible sheet of cushioning material showing my new design;

Fig. 2 is an edge view taken from the bottom edge of that shown in Fig. 1; while,

Fig. 3 is an edge view taken from the right edge of that shown in Fig. 1.

I claim:

The ornamental design for a flexible sheet of cushioning material or the like, substantially as shown.

LESTER PANNONE.
